4 Claims. (Cl. 250—27)

1

This invention relates to the utilization of the oscillatory activity of electrically-charged particles in a vacuum.

It is an object of my invention to provide an electronic oscillatory device having a vacuum tube in which electrons may be held initially in static equilibrium within the evacuated space, and so arranged as to number and distribution that, when the device is acted upon by alternating voltages, the electronic space charge will be set into oscillation in such a manner that the device will display to the alternating voltages the properties of a parallel-resonant circuit and, alternatively, the properties of an amplifier of the alternating voltages.

This invention further contemplates the generation of alternating voltages.

Other objects and advantages of the invention will become apparent as the description proceeds. Reference will now be made to the accompanying drawings wherein like reference numerals indicate like parts.

Figure 1 is a simplified schematic view of a basic form of invention as an electronic oscillatory device.

Figure 2 is a simplified schematic view of a modified form of the invention as a push pull amplifier.

Figure 3 shows a fragmentary partly cross-sectional view of one form of electronic tube which may be used to realize the advantages of this invention.

Figure 4 shows an elevation view of another form of tube which may be used.

Figure 5 shows a fragmentary partly cross-sectional view of still another form of electronic tube which may be used.

Referring to Figure 1, an evacuated envelope or tube is shown at 1, which may be of glass or other insulating material. In the end regions of tube 1 are cathodes 3 and 5 activated by power sources 7 and 9, preferably through variable resistances 8 and 10. Electrically connected to cathodes 3 and 5 are reflectors 11 and 13. It is not essential that tube 1 have two cathodes, but it is recommended that both reflectors 11 and 13 be provided. An anode 21 to be described later, is shown in the central region of tube 1, and D.C. source 15 is connected to reflectors 11 and 13 through choke coils 17 and 19 and to anode 21 in such a manner that reflectors 11 and 13 are normally at a potential negative with respect to ground. The purpose of the elements just described is to produce a charge of electrons inside tube 1 and to hold the charge of electrons normally in equilibrium between reflectors 11 and 13. With electrons thus held in equilibrium in the central region of tube 1, reflectors 11 and 13 may be acted on by oscillation generator 27, connected to the reflectors through D.C. blocking

condensers 29 and 31. The charge of electrons may thus be made to oscillate in response to the alternating voltage supplied by oscillation generator 27.

Anode 21 has been referred to above. In one form as shown in Figures 3 and 5 anode 21 will be an annulus so placed that its inner surface lies in contact with the evacuated space but slightly depressed with relation to the inner surface of the glass envelope, to the end that electrons passing through the central region will have a low component of velocity towards the anode. Anode 21 is connected to resistance 23 which may be either fixed or variable and which in turn is connected to the grounded or ungrounded positive side of D.C. source 15. Reference character 25 designates a capacitance connected across resistance 23. In Figure 1, if oscillation generator 27 is inactive but cathodes 3 and 5 are activated by power sources 7 and 9, D.C. source 15 will cause a current to flow from the D.C. source to cathodes 3 and 5, to anode 21 and thence back to D.C. source 15 through resistance 23. To sustain the current against the negative potential of anode 21 caused by the voltage drop across resistance 23 and against the repulsion of electrons further advanced along the path to the anode, an electronic space charge will grow in the central region of tube 1.

If the rate of electron flow towards the central region of tube 1 is limited by filament saturation of the cathodes 3 and 5 or by the interposition of negatively biased grids in the electronic path to the anode, or by other means, the negative voltage applied to reflectors 11 and 13 may be so adjusted that the space charge will consist of a small number of high velocity electrons in the regions of the cathodes and a great number of electrons moving with negligible velocity near the anode, so that for the purposes of the present discussion of the invention, the principal mass of the electrons can be regarded as being held in static equilibrium by the negative voltages applied to the reflectors 11 and 13. The degree to which the space charge is compressed towards the central region can be controlled by varying the reflector voltages simultaneously and in the same direction, while the number of electrons contained in the space charge can be altered by varying resistance 23.

With the reflector voltages equal and the electrostatic field distribution between the reflectors 11 and 13 and anode 21 established in a regular manner, either due to the dimensions and symmetry of these elements alone or as aided by extensions thereof external to the evacuated space, the space charge will be symmetrical about the anode. If, now, the reflector voltages are made to differ, the equilibrium of the space charge will be upset and it will move to a new position

towards the less negative reflector. This movement is an electric current which will set up a magnetic field in which energy is stored while the electrons are being accelerated, to return it to them in support of their velocity when they begin to slow down. The amplitude of the current is determined by the number and velocity of the electrons.

The standard definition of electric current defines a flow and not a velocity. The definition is satisfactory for closed metallic circuits where the positive charge produced by the departure of an electron from an atom is neutralized by the arrival of a following one, so that all of the free electrons present may take part in the movement around the circuit as a cohesive mass, but is less applicable where the electrons must be regarded as a limited number of discrete particles.

In the invention, for instance, all of the electrons of the space charge might, by some means, be compacted into a single plane and the plane caused to oscillate back and forth. Then, except for the very end regions of their path, the electronic flow past every point would be the same, but the velocity of the electrons in the center of the path might be vastly greater than where they come to rest. Since the intensity of the magnetic field surrounding an electron is proportional to its velocity and in a metallic circuit the magnetic field is proportional to current, the difficulty with the standard definition of current is apparent.

Since, by definition, an electric current is a flow, the expression for the energy stored in a magnetic field involving current and inductance can be reconciled with a similar expression for the invention involving the number and velocity of the electrons only if, in the latter, the number of electrons is inversely proportional to their inductance. That this is true may be shown by a simple explanation.

If two electrons having the same velocity and direction are moving in tandem, their inertia will be due to the magnetic field of each referred only to its own electron, and to the gravitational mass of the electrons. If the two electrons are moving as a pair, however, their two magnetic fields will interlink and each electron will tend to force the other in the opposite direction whenever any change in their velocity takes place, thus giving to both an inertia not due to an increase in the total energy stored in the magnetic fields and hence more nearly gravitational in effect. It follows that, in the invention, the more the electrons are compacted towards the central region, that is, the greater their inductance, the smaller will be the number required to produce a specified total of electrical inertia, but with a corresponding reduction in electromagnetic action, when the mass moves with a given velocity, either in free space or in any following circuit.

With no space charge present, the reflectors 11 and 13 will have a definite capacitance to the terminals of generator 27 which will be unaltered by the negative voltage applied thereto, although this voltage will apply a negative charge to each of the reflectors 11 and 13 upon which any charge from the generator will be superimposed. When the space charge is introduced, the repulsion of its negative charge will reduce the negative charges on the reflectors 11 and 13 and make their relative magnitudes dependent upon the position and symmetry of the space charge. Movements of the space charge can therefore produce a charge and discharge of the reflectors

11 and 13 which is not necessarily in phase with the charge and discharge of the conventional capacitance produced by the generator voltage. If blocking condensers 29 and 31, and choke coils 17 and 19 are adequate to their respective purposes, this electronic capacitance will react only on the generator; and if for some frequency the two capacitive reactions are equal and opposite, the reflectors 11 and 13 will be non-reactive to the generator, provided any variations in cathode to anode direct electronic flow are small enough to be neglected.

In the resistanceless case if the circuit from generator 27 to the reflectors 11 and 13 is closed at the instant when its alternating voltage is at a peak, the space charge will begin immediately to move towards the reflector to which the positive peak of alternating voltage is applied, driving electrons freely out of the latter towards the positive terminal of the generator, with a reciprocal action occurring at the opposite reflector. Being unopposed, the space charge will be continuously accelerated until the instantaneous alternating voltage difference between the reflectors 11 and 13 falls to zero, with energy being stored by the space charge throughout this time interval to sustain its velocity after the acceleration ceases.

When the generator voltage begins to go negative to the nearer reflector, it will begin to resist the free flow of electrons therefrom. The effect of this is to build up a force of repulsion between the reflector and space charges which is directly proportional to their product and is an inverse function of the distance between their electrostatic centroids. If the alternating voltage is low enough, but within certain limits imposed by the device, the moving space charge will have enough energy stored by it to continue driving electrons away from the reflector until the associated generator terminal reaches a negative peak of voltage. At this instant, because the line integral of the force opposing the motion is now equal to that which produced it, the movements both of the space charge and the electron flow with respect to the reflector must reverse themselves.

Because of its displacement from the position of central equilibrium the space charge will be more rapidly accelerated on its return journey than during the initial quarter-cycle with the result that, during this or a subsequent movement, it will reach its maximum velocity at the instant when it is again symmetrical about the central anode and moving in the direction of the reflector then about to go negative to the alternating voltage, and the instantaneous alternating voltage difference between the reflectors, of necessity, is zero. Considerations of symmetry will show that for any frequency steady state oscillations will be possible only under these last conditions. Therefore, the charge and discharge of the electronic capacitance of the reflectors, whenever the space charge is acted upon by a single alternating force, will always be diametrically opposed to that of their conventional capacitance and hence the effect of the former is that of an inductive reactance.

The reactance of the device will be purely inductive for low frequencies. As the frequency is increased, however, the displacement of the space charge and hence of the reflector charge in phase with it will decrease while the charge and discharge of the conventional capacitance per cycle remains constant. Therefore, at some

one frequency, the two rates of charge will be equal and opposite and the impedance to the generator will be infinite. Above this frequency the reactance will be purely capacitive and decreasing with increasing frequency. These are the conditions which obtain in a parallel-resonant network.

If the cathode to anode direct currents do not vary during the operating cycle, they will not affect resonance regardless of their amplitude. If they do vary, they will cause a charge and discharge of the reflectors which, if diametrically opposed to that tending to be produced by the generator voltage, will serve to increase the inductive current and resonant frequency. If the phase relation is other than this, the space charge will shift the phase of its oscillations to respond to the resultant, the effect being that of adding series capacitance to the parallel network. When resistance is present, the initial displacement of the central space charge will fall short of what it should be and the space charge will turn back before the charge of the reflectors by the generator is complete. When steady state oscillations have been attained, the charge and discharge of the reflectors will remain out of phase with the generator voltage and thus replenish the energy being lost by the space charges.

The space charge may also be set into oscillation by an alternating field coupled to it either from a metallic circuit or a similar space charge. In this case the charge and discharge of the reflectors caused by the movements of the space charge will produce currents and voltages for the operation of a following network. Furthermore, in view of the facts that the proportions of the electromagnetic and inductive inertias of the space charge can be varied while maintaining the total constant and that only the electromagnetic inertia will affect a coupled circuit, the degree of coupling can be altered simply by varying the D. C. potentials applied to reflectors and anode without affecting resonance.

When the space charge is moving with high velocity, few electrons will be absorbed by anode 21 because their velocity parallel to its surface will be high compared to that normal to it. Capacitance 25 is intended to maintain the potential of the anode reasonably constant during the cyclic variation in electronic absorption. Anode 21 may be completely external to the evacuated space of the invention and both resistance 23 and capacitance 25 dispensed with; but in this form of the invention the number and distribution of the electrons in the space charge would be more difficult to control. If grids are interposed between cathodes and anode for the purpose, their effectiveness will be limited unless a variable impedance network is used to divide the output voltage of generator 27 between reflectors and grids.

Two effects pertaining to inherent properties of the invention will now be discussed. The first arises from the fact that the space charge is not a rigid mass but is capable of compression within itself. The second is the modification of the action of the space charge which will take place if use is made of an external positively charged anode.

Compression within the central space charge will vary as it approaches or leaves a reflector depending on how loosely the electrons are compacted initially. This will produce an effect equivalent to that of the distributed capacitance of a coil. As is well known, distributed capaci-

tance can produce the effect of parallel resonance in a coil without the aid of any other capacitance. Consequently, in the invention, even though the inter-reflector capacitance were negligible, resonance could occur. Space charge resonance seems to require that groups of electrons in the end regions become motionless while oscillations continue in the more central region.

This can happen because the reflector charge with its fixed location but variable number of electrons can exactly counterbalance the effect, on a nearby group of space electrons, of the relatively fixed number of electrons but variable position of the central part of the space charge. As the frequency is increased above resonance, the electrons in the end regions of space will begin to move counter to the direction of the more central mass, thus making the net effect of the space charge, as seen from the reflectors, capacitive rather than inductive as hitherto described.

The action considered above is progressive with frequency, the three groups of space electrons tending to sub-divide into five, with the two new groups taking both from the central mass and the first two end groups and the overall effect becoming once more resonant and then again inductive to the reflectors in a manner analogous to the successive resonant points of a metallic antenna. This theory is subject, of course, to the modifications introduced by the fact that changes in velocity of electrons are not transmitted from one to another instantly but with the speed of light.

The capacitance established by the dimensions and spacing of the reflectors was shown to be a resonant-frequency determining quantity. This capacitance can be increased by extending the reflectors externally to the evacuated space and reinforced where desired by additional fixed or variable capacitance across the reflectors. Skin-effect will cause the space charge, when in motion, to press against the inner surface of the tube 1 and thus produce what may prove to be, in some applications, an objectionable power loss. One means of focussing the electrons more towards the axis of their movement is to divide the reflectors concentrically to this axis, in the region of the glass wall of the envelope. The two parts may then have different negative voltages applied to them through separate choke coils, with the more negative voltage applied to the outer ring, but may be capacitively coupled for unity of action with respect to an alternating voltage.

For simplicity and economy in design, the invention may be modified by having a cathode at only one end of tube 1, with a reflector alone at the other end. Neither the symmetry of the space charge nor the theory of operation will be appreciably affected by this change. Two or more anodes in regions approaching the reflectors and controlled as to potential either separately or together, with the space charge extending towards the central region as before, are also contemplated. It is intended that tube 1 may have any desirable form whatsoever, and more particularly a form which will facilitate the establishment of a larger space charge, such as one having a larger cross-section in the central region than in the end regions, as shown in Figure 4. Also, the use of a double-walled tube with the evacuated space between the walls is envisaged, as shown in Figure 5, where the outer wall is denoted by 1a and the inner wall by 1b.

The reflectors may in this construction be divided into two portions, annular portion 11a and cylindrical portion 11b.

Thus either by the mechanical restrictions imposed by walls of glass or other insulating material or by the action of axially graded electric fields or both, it is possible to confine the space charge, when at rest, within the ring-shaped or other zone normal to it when in motion.

The invention originated in an extended search for a short device to replace the long wires used for the radiation and reception of electric waves. The amount of energy supplied to the radiation field, in either case, will depend solely on the number and velocity of the electrons producing the field, with a reciprocal relationship for reception. In a metal wire antenna the active electrons are so strung out along its length that their inductive effect upon one another may be small and their number large as compared with the closely compacted electrons of the invention. On the other hand, the velocity of the electrons will be checked only by the losses of power either by radiation or internal or local to the radiator. As a conductor of electrons, evacuated space is so nearly lossless compared with any metal that the possibility of high efficiencies of radiation and reception is apparent even with much higher relative inductances.

Referring now to Figure 2 of the drawing, this differs from Figure 1 principally in that grids 33 and 35 negatively biased with respect to ground through choke coils 37 and 39 by D. C. voltage source 41, are shown interposed between cathodes and anode. Although generator 27 is shown as applying its voltage to grids 33 and 35 instead of to the reflectors 11 and 13, this is an alternative and not an essential change. The principal difference in operation is that, in the form shown in Fig. 2, the cathodes are required to supply electrons, not merely at a minimal rate to establish and maintain the space charge in resonance, but at a higher rate to do this and to drive the space charge back and forth by electronic impulsion. With these differences in view the space charge may be regarded as being established substantially so described for Fig. 1, but with the cathode to anode currents determined by the magnitudes of the space charge and the negative charges of cathodes reflectors and grids.

If, now, grids 33 and 35 are excited by an alternating voltage from generator 27 which never exceeds the cut-off value for the cathode to anode currents, the total electron flow towards the anode will remain the same as for the steady grid voltage but will vary cyclically in volume from one end region to the other, thus creating an alternating force against the space charge which will depend on the instantaneous differences in the number, velocities and positions of the electrons moving towards the space charge from the two end regions. This force will cause the space charge to oscillate at the frequency of the alternating grid voltage.

The area of the grids 33 and 35 is assumed to be so small that their electronic charge is not a resonance-determining quantity, while the inter-reflector capacitance is not, as in Fig. 1, connected across generator 27. Each of the reflectors, however, in addition to the inter-reflector capacitance referred to above, possesses a capacitance with respect to the anode and its return path to power source 15 which can be established substantially as described in connection with Fig. 1. With the space charge oscillating and choke

coils 17 and 19 tending to maintain the direct electron flow constant, there will be a charge and discharge of these capacitances reciprocal to the amplitude of the cathode to anode electronic flow. The movement of the space charge will be towards the cathode whose charge with that on its associated reflector is increasing and will continue, due to the momentum imparted to its mass, after the electronic impulse from the opposite cathode has ceased. The space charge will turn back when the electrostatic centroid of the reflector charge and its projection towards the space charge due to the release of electrons through the grid is close enough to that of the space charge to bring it to a halt. The space charge will oscillate with maximum amplitude and present the effect of a pure resistance in the cathode to anode circuits, when it is so proportioned to the reflector charges that the space charge comes to rest at the instant when the electronic current towards it is at a maximum, that is, when the grid reaches its positive peak of alternating voltage.

Since the momentum imparted to the space charge depends on the instantaneous difference between the two cathode to anode currents, it is desirable that the current from each cathode be cut off during at least a half-cycle of each alternation. If the grids are so biased, resistance 23 may be readjusted to establish resonance for a new average rate of electron flow, but variations in the amplitude of grid excitation will detune the space charge. This can be prevented by maintaining the voltage of anode 21 substantially at the value negative with respect to ground required for resonance by means of a direct current through resistance 23 provided by any power source through a suitable choke coil. Electrons will then be taken from the space charge only when the electronic pressure on the anode raises its voltage to or slightly above the value determined by the power source. This connection will improve the power efficiency of the device itself but apparently not that of the circuit as a whole. Furthermore, since the negative voltage of anode 21 is a resonance-determining quantity, the invention can be frequency-modulated, either in an oscillator or otherwise, by applying an audio or other frequency voltage from a generator suitably connected across resistance 23.

In a conventional vacuum-tube amplifier, most of the momentum of the electronic impulses is abruptly lost as heat to the anodes where, in addition to the heating problem, the discontinuity in velocity coupled with the uni-directional conductivity of the anodes leads to transit time difficulties at high radio frequencies. In this invention, the anodic effect of the space charge is completely bi-directional; there is no discontinuity in the velocity of the electrons because the momentum of the electronic impulses is gradually imparted to the space charge; and comparatively little heating will occur within the device because the electrons leaving the space charge ordinarily fall through a very small voltage difference in striking the anode. While heating will occur in resistance 23, this element is external to the device where the problem of heat dissipation is more easily solved.

A contributing factor to the amplifying properties of the device of Figure 2 of the drawing is that the charge and discharge of the reflectors act in synchronism with the grid voltage variations to determine the magnitude of the electronic impulses towards the central space charge.

If the inter-reflector capacitance is great enough, the oscillatory activity of the space charge will be reinforced until it takes control and the device becomes self-oscillatory.

Generator 27 may then be dispensed with and the grids used only as negatively charged elements to aid in controlling the duration but not directly the frequency of the electronic impulses towards the central region. As a simplification the grids themselves may be eliminated and the form of the oscillator reduced to that of Figure 1 of the drawing.

It is to be noted particularly that in these simplified oscillators the varying reflector charge need not reside in the metal of the reflectors but may be in the adjacent evacuated space, as discussed in connection with Figure 1 of the drawing. The oscillatory activity will then take place entirely in space, with the metal members serving only as boundaries to this activity and as carriers of the constant amplitude direct currents which provide the driving power of the oscillator. It is at once apparent that since the metal members do not limit the upper frequency, generation and utilization of waves of extremely short length is possible.

The description discloses an electronic counterpart of the metallic tuned circuits used in the radio and allied arts. In a usual form it provides a charge of electrons held in space in neutral or unstable equilibrium to two other countervailing and mutually opposing charges; but by a transition of values it can graduate to a charge of electrically-charged particles held in space in stable equilibrium to an external positive charge. The invention is capable of replacing coil and condenser circuits, line tanks, cavity and wire resonators in a wide variety of combinations and applications of which only the most fundamental are described herein.

In a useful form, the invention displays the characteristics of a parallel-resonant circuit but it goes far beyond this. Modifications in the internal activity of the space charge or changes in the direction from which its electrical characteristics are explored can cause it to assume many other manifestations. If, when the space charge of electrons is acted upon by an oscillating electric force, it possesses in relation to the activating force the electrical equivalent of inertia, it is this invention. Where the expressions "electric force" or "electric field" are used in the specification and claims, they are intended to include any and all electromagnetic and electrostatic phenomena which may be applicable. Also where the device is referred to as a radiator of electric waves, its properties as a receiver of electric waves are intended to be included.

It will be observed that the invention in its basic forms has an outward appearance of great simplicity; but in the electronic art, invention may reside in the physical quantities which are the numbers, positions, velocities and directions of motion of electrons in free space, equally as well as in the metallic electrodes and other more easily represented parts of a circuit. So it is in the present invention. For these spatial activities, theories of performance rather than concrete physical representations have been referred to in the description. The intent of the inventor is to be held to the truth of matters of theory only to the extent that the essence of the invention will stand or fall thereby.

What is claimed is:

1. An electronic network comprising an evacuated envelope, electron emitting means within

said envelope, electron reflecting means in said envelope, anode means having at least one surface thereof exposed to the inside of said envelope, a current source attached to said electron emitting means, said electron reflecting means and said anode means, the negative side of said current source being attached to said reflecting means through R. F. blocking means and the positive side being attached to said anode means through impedance means.

5 2. An electronic resonator comprising an elongated evacuated envelope, electron emitting means within said envelope, a plurality of electron reflecting plate means at least partly inside said envelope and disposed perpendicularly to the length of said elongated envelope, anode means having at least one surface exposed to the inside of said envelope and a current source connected to said electron emitting means, said electron reflecting plate means and said anode means with such polarity that electrons tend to move from said electron emitting means toward said anode means, and oscillation generating means connected to said electron reflecting plate means.

15 3. An electronic network capable of amplifying signals applied thereto or of producing oscillations comprising an evacuated envelope, electron emitting means within said envelope, a pair of substantially parallel electron-reflecting plates at least partly inside said envelope, and at least one of said electron reflecting plates being connected to said electron emitting means, anode means disposed between said electron reflecting plates, a current source connected to said electron emitting means, said electron reflecting plates and said anode means in such relationship that electrons tend to move from said electron emitting means toward said anode means and said electrons are repelled from opposite directions by said electron reflecting plates, the said current source being connected to said electron reflecting plates through R. F. blocking means.

20 4. A push-pull amplifier comprising an evacuated envelope, electron emitting means in said envelope, and anode having at least one surface thereof exposed to the inside of said envelope, two electron control means disposed substantially symmetrically about said anode, two electron reflecting plates disposed substantially symmetrically about said anode, at least one of said electron reflecting plates being connected to said electron emitting means, a current source having its positive side connected to the anode and its negative side connected to the electron reflecting plates through R. F. blocking means, the input to the said push-pull amplifier being received between said two electron control means.
